UNITED STATES PATENT OFFICE

WILLIAM KEATH SUMMERHAYES, JR., OF LOUISVILLE, KENTUCKY

SIGN BRACKET

Application filed March 11, 1929. Serial No. 346,197.

This invention relates to improvements in sign brackets, and has for one of its principal objects the provision of a bracket for so positioning and displaying signs, placards, notices, pennants, advertisements, and the like as to render them readily visible and noticeable.

This application constitutes an improvement on applicant's prior patented device 10 entitled "Advertising devices" dated September 25, 1928, No. 1,685,102, and a further improvement on applicant's pending application for patent on "display brackets" filed April 15, 1927, Ser. No. 184,028.

One of the important objects of this invention is to provide in a display bracket or the like a simple unitary device which can be readily clamped about and supported upon an extension or projection of some sort such 20 as a door handle or the like whereby a signal or sign may be conveniently and readily displayed.

Another and further important object of this invention is the provision in a sign bracket of means for displaying a signal particularly available to motorists so that when any trouble is encountered or service required the user may simply attach a signal to the door of his automobile by means of this 30 bracket which signal will automatically indicate to a passing serviceman that his attention is required upon the car displaying the said signal.

A still further and important object of this invention is the provision of a signal displaying means particularly for motorists which is compact, readily available for use at all times, and which is so inexpensive that it can be distributed gratis by service organizations to motorists becoming members of such organizations or desiring to avail themselves of the facilities provided.

Other and further important objects of the invention will be apparent from the disclosures in the accompanying drawings and following specification.

The invention, in a preferred form, is illustrated in the drawings and hereinafter 50 more fully described.

In the drawings:

Figure 1 is a side elevation of the sign bracket of this invention showing the same as applied to a door handle of a motor car or the like.

Figure 2 is a perspective view of the bracket itself.

Figure 3 is a plan view showing the stamping from which the bracket is formed.

Figure 4 is a side elevation illustrating a 60 modification of the invention showing its application to a door knob or other similar projection.

Figure 5 is a sectional view taken on the line 5-5 of Figure 4 illustrating another 65 adaption of the modification.

As shown in the drawings:

The reference numeral 10 indicates generally the sign supporting arm of the improved sign bracket of this invention, the same comprising merely flat pieces of metal or the like bent into channel shape form as best shown in Figure 2. At the inner end of the arm are positioned integral upstanding ears 12 which are also bent together as best shown in Figure 2, but which have their upper outer ends flared outwardly so as to readily slip over and grip the shank 14 of the handle 16 of an automobile door or the like 18.

Adjacent the point of juncture of the ears 12 with the shank 10 of the bracket the same is flared slightly as shown at 20 so as to render the device readily adaptable for various shapes and sizes of automobile door handles while at the same time affording a quick, secure, and convenient means of positioning the bracket upon the handle. In the position shown in Figure 1, a placard or similar object 22 is inserted into the channeled upper face of the arm 10, and the placard is of such thickness with respect to the channel that it will be frictionally gripped thereon and supported in an upright position whereupon any sign or indicia upon the placard will be readily visible to passersby.

In the case of a sign requesting assistance or service this naturally will receive prompt attention and instant recognition.

From an inspection of Figure 3, it is evident that the device may be readily shaped 100.

from a single stamped out sheet of material, preferably slightly resilient metal, so that the gripping action of the co-ordinated ears 12 will be positive.

5 In the modification shown in Figure 4 an outstanding arm 30 is provided formed in channel shape but having the opening downwardly, and with its lower edges 32 bent upwardly and inwardly to provide a frictional gripping element for a sign, placard, flag, pennant or the like 34. It will be further noted that an integral extension 36 of the arm 30 is provided, this extension being approximately semi-circular in form and curved downwardly so as to fit under a handle or conventional door knob 38 while at the same time the ends 40 are shaped similarly to the ears 12 so as to surround and securely grip the shank 42 of the knob 38.

20 It will be evident that hereby is provided a means for effectively displaying flags or pennants of cloth or similar material, thereby eliminating the placard feature, making the device slightly more compact, as the flag or pennant may be simply wrapped around the shank 30 when the apparatus is not in use. Further, the adaptation of the downwardly curved connecting element 36 renders the device capable of a wider variety of uses.

25 It will be evident that herein is provided a sign bracket which is capable of many uses especially as an emergency signal for motorists requiring but an instant to attach and making it easy for the service man to locate 30 a particular car whether on the street, in a parking field, or some other congested district. Further, it enables the user to proceed about his business with the assurance that the car will be promptly located and 35 properly serviced, as instructions may be readily placed upon the bracket, either directly upon the sign board or pennant or upon a separate card or piece of paper also wedged into the channel. Again, it permits 40 the user to wait in comfort for services after having displayed the signal and eliminates 45 the danger of being run down while attempting to hail passing motorists or others for aid.

50 I am aware that many changes may be made, and numerous details of construction varied throughout a wide range without departing from the spirit of this invention, and 55 I therefore do not purpose limiting the patent granted hereon otherwise than as necessitated by the prior art and the appended claim.

I claim as my invention:

60 A sign bracket comprising a plate formed of a single sheet of material having a sign supporting element comprising an arm of the plate bent into channel-shaped form together with a pair of object-gripping elements integral with the channel arm, and off-

set therefrom, said offset portions including a substantially semi-circular connection between the gripping elements and the arm.

In testimony whereof I affix my signature.

W. KEATH SUMMERHAYES, Jr.
